UNITED STATES PATENT OFFICE.

THOMAS VINCENT CONNOR, OF DENVER, COLORADO.

DESIGN FOR A PRESSURE-COOKER.

58,662.

Specification for Design.

Patented Aug. 9, 1921.

Application filed January 24, 1921. Serial No. 439,697. Term of patent 14 years.

To all whom it may concern:

Be it known that I, THOMAS V. CONNOR, a citizen of the United States, residing at the city and county of Denver and State of Colorado, have invented a new and original ornamental Design for Pressure-Cookers, of which the following is a specification, reference being had to the accompanying drawing, forming a part thereof.

In this drawing:

The figure is a side elevation, showing my new design.

I claim:

The ornamental design for a pressure cooker, as shown.

In testimony whereof I affix my signature.

THOMAS VINCENT CONNOR.
